UNITED STATES PATENT OFFICE

2,520,343

POUNCE BAG FOR DUSTING MOLDS

George E. F. Saum, Chicago, Ill.

Application April 22, 1948, Serial No. 22,641

5 Claims. (Cl. 15—131.1)

1

In order to secure acceptable results, molds for use in the formation of thermoplastic materials require frequent "lubrication" through the application of a powder. Generally the material powdered for such use is zinc stearate.

Heretofore it has been the practice to place a quantity of this powder on a piece of cloth—usually a rag or material discarded from other uses—and after drawing the perimetal portions together tying and/or taping the gathered portions to provide a grip for the hand to permit the banging of the powder bag against the mold. All too often this has presented problems. Such cloth as would permit the sifting of the powder would result in an excess emission of powder onto the mold. Not infrequently such cloth has been of such a nature as to be easily injured by the mold, resulting in the cloth breaking. When that happens a mold becomes fouled with an excessive amount of powder, too often resulting in defective pieces being produced by the subsequent use of the mold. Moreover, aside from the waste, the dust gets into the press bearings, causing excessive wear, and the air becomes filled with dust which is detrimental to the health of workmen.

The main objects of this invention, therefore, are to provide an improved form of pounce bag for use in dusting molds, particularly metal molds used for forming thermoplastic materials; to provide an improved bag of this kind capable of effecting an even and uniform sifting of the powder but so formed as to long resist deterioration with its consequent excessive emission of powder and breaking of the bag resulting from extended recurring striking thereof against the corners, edges, and protuberances of the mold configurations; to provide an improved bag construction of this kind comprising superimposed layers of fabric of differing characteristics of thread one of which is adapted to sift the powder and the other of which is adapted to resist wear; to provide an improved fabric arrangement of this kind the perimetal portions of which can be gathered to enclose the powder and form a hand grip convenient for holding the bag during the pouncing operation; to provide improved draw-string means for gathering the perimetal portions of said layers of cloth to form the bag and lacing the same together so as to make highly convenient the filling, closing, and subsequent refilling of the bag; and to provide an improved pounce bag of this kind which is inexpensive to make, efficient in use, and of great durability.

In the drawings,

2

Fig. 1 is a perspective view of a preferred form of pounce bag, constructed in accordance with this invention, the perimetal portions being laced together as they would normally be to enclose the powder and form a hand grip. When initially filled with powder the bag part would have a much more extended bag part than here shown;

Fig. 2 is a plan view of the ungathered superimposed layers of cloth as viewed from the exposed side of the coarser material, the ends of a draw-string enclosed in a perimetal casing being threaded through the end eyelets in the tucks bordering the radially-disposed gore;

Fig. 3 is a similar view taken from the opposite or inside of the superimposed layers;

Fig. 4 is an enlarged diagrammatic cross-sectional view of the gore and tucks taken on the line 4—4 of Fig. 2;

Fig. 5 is an enlarged diagrammatic cross-sectional view of the perimetal portion of the superimposed layers, taken on the line 5—5 of Fig. 2;

Fig. 6 is a view similar to Fig. 2 showing a modified arrangement of the draw-string;

Fig. 7 is an opposite or inside view of the same;

Fig. 8 is a perspective view similar to Fig. 1 but showing the form the folds take with the modified arrangement of the draw-string shown in Figs. 6 and 7;

Fig. 9 is an enlarged diagrammatic cross-sectional view of the gore and tucks for the modification shown in Fig. 6, taken on the line 9—9 of Fig. 6; and

Fig. 10 is an enlarged diagrammatic cross-sectional view of the perimetal portion of the modification shown in Fig. 6, taken on the line 10—10 of Fig. 6.

A pounce bag constructed in accordance with this invention comprises two superimposed circular layers of cloth 11 and 12 stitched together around their perimetal portions and also stitched together along lines nearly radial to form a radially-disposed gore section 13 bordered by tucks 14. A draw-string 15, threaded through the perimetal portions of these superimposed layers and through the tucks 14, is adapted to gather said perimetal portions together to form a bag or container for powder and provide a hand grip for convenient use in holding the bag when striking it against the mold so as to sift powder on the surfaces thereof.

The layers of fabric 11 and 12 are of different character, one designed to serve as a sieve, the other to resist wear. To that end the inner layer

11 is formed of comparatively fine threads, whereas the outer layer 12 is formed of coarser threads.

The inner layer 11 is thus a fabric much like that from which flour sacks are made, through which the powdered material is adapted to be sifted. On the other hand, the outer layer 12 is a fabric in the nature of light duck or canvas. This outer layer 12 has far greater durability and resistance to wear than does the inner layer 11, thus providing an extended life for the bag.

In the preferred form, as shown in Figs. 1 to 5 inclusive, the stitching of the layers around their perimetrical portions is such as to provide a casing 16 in which to contain the lacing or draw-string 15.

In the modified form, as shown in Figs. 6 to 10 inclusive, the same perimetrical stitching is provided. However, eyelets 17 are secured around this perimetrical casing portion of the layers at circumferentially spaced points.

The gore section 13 is formed by stitching the layers together along nearly parallel and substantially radially-disposed lines so as to form a section within which the gathered perimetrical portions of the superimposed layers may be drawn by the draw-string 15. In either modification, spaced eyelets 18 are fixed in the tucks 14 through which the draw-string 15 may be threaded.

The lacing or draw-string 15 is of conventional character and, as indicated, may either be enclosed in the perimetrical casing 16 as shown in Fig. 5 or threaded through the perimetrical eyelets 17, as shown in Figs. 6, 7, and 8, with the free ends in either case threaded through opposite eyelets 18 formed in the tucks 14.

A pounce bag constructed in accordance with either of the modifications herein shown is used in the following manner.

A quantity of powdered material is placed in the center of the inner layer of cloth 11. The surrounding perimetrical portion of the layers is gathered up around the powdered material and the draw-string 15 drawn up to bring the perimetrical portions close together. The ends of the draw-string are then threaded through the eyelets 18 in the tucks 14 embracing the gathered portion of the layers. As the string 15 is drawn up the gathered portion of the layers 11 and 12 is compressed into the space between the tucks 14, and provides a hand grip which may be grasped for striking the bag part against the mold so as to sift the powder onto the surfaces thereof. When it is desired to replenish the powder in a bag of this character it may be very conveniently done by simply unlacing the draw-string 15, pulling apart the gathered perimetrical portions, pouring a quantity of powder, and again drawing up the lacing 15.

Other variations and modifications in the details of structure and arrangement of the parts may be resorted to within the spirit and coverage of the appended claims.

I claim:

1. A pounce bag for use in dusting molds comprising superimposed coextensive layers of powder-pervious woven fabric one of which layers is formed of comparatively fine threads adapted primarily to provide a sifter for powder and the other of which layers is formed of threads comparatively tougher than the threads for said one layer and thereby adapted to provide a covering with a high capacity for resisting wear caused by striking the bag against the mold, and means for gathering the perimetrical portions of said

superimposed layers of fabric to form a container for the powder and provide a hand grip by which to hold the pounce bag when striking the mold.

5. A pounce bag for use in dusting molds comprising superimposed coextensive circular layers of powder-pervious woven fabric one of which layers is formed of comparatively fine threads and woven primarily to provide a sifter for powder and the other of which layers is formed of threads and a weave adapted to provide a covering with a maximum capacity for resisting wear caused by striking the bag against the mold, said layers being stitched together along their perimetrical portions to form a casing, and a draw-string arranged in said casing to permit the gathering of the perimetrical portions of said superimposed layers of fabric to form a container for the powder and provide a hand grip by which to hold the pounce bag when striking the mold.

3. A pounce bag for use in dusting molds comprising superimposed coextensive circular layers of powder-pervious woven fabric one of which layers is formed of comparatively fine threads and woven primarily to provide a sifter for powder and the other of which layers is formed of threads and a weave and adapted to provide a covering with a maximum capacity for resisting wear caused by striking the bag against the mold, said layers being stitched together to form a radially-disposed gore section bordered by tucks, eyelets formed in said tucks, and a draw-string slidably attached to the perimeter of said superimposed layers and adapted to be threaded through the eyelets in said tucks whereby the drawing of said string will gather the perimetrical portions of said superimposed layers of fabric to form a container for the powder and fold the gathered portion of said layers between said tucks so as to provide a hand grip by which to hold the pounce bag when striking the mold.

4. A pounce bag for use in dusting molds comprising superimposed coextensive circular layers of powder-pervious woven fabric one of which layers is formed of comparatively fine threads closely woven so that it is adapted to sift powder therethrough and the other of which layers is formed of coarser threads than the threads for said one layer and likewise closely woven and adapted to provide a covering with a maximum capacity for resisting wear caused by striking the bag against the mold, said layers being stitched together to form a radially-disposed gore section bordered by tucks, eyelets formed in said tucks and in the perimetrical portions of said superimposed fabrics, and a draw-string threaded through the eyelets in said perimetrical portion and adapted to be threaded through the eyelets in said tucks whereby the drawing of said string will gather the perimetrical portions of said superimposed layers of fabric to form a container for the powder and fold the gathered portion of said layers between said tucks so as to provide a hand grip by which to hold the pounce bag when striking the mold.

5. A pounce bag for use in dusting molds, comprising superimposed, coextensive, circular layers of powder-pervious woven fabric, one of which layers is formed of fine threads and woven primarily to provide a sifter for powder and the other of which layers is formed of threads and a weave adapted to provide a covering with a maximum capacity for resisting wear caused by striking the bag against the mold, said layers

ing stitched together to form a radially-disposed gore section bordered by tucks, eyelets formed in said tucks, and a draw-string threaded through the eyelets of said tucks, whereby the drawing of said string will gather the perimetrical portions of said superimposed layers of fabric to form a container for the powder and fold the gathered portion of said layers between said tucks so as to provide a hand grip by which to hold the pounce bag when striking the mold.

GEORGE E. F. SAUM.
